FRANK LANTIERI AND GABRIEL LANTIERI, OF JERSEY CITY, NEW JERSEY.

ADJUSTABLE CLAMP.

1,395,839.

Specification of Letters Patent.

Patented Nov. 1, 1921.

Application filed April 28, 1921. Serial No. 465,154.

To all whom it may concern:

Be it known that we, FRANK LANTIERI and GABRIEL LANTIERI, citizens of the United States, residing at Jersey City, in the county 5 of Hudson and State of New Jersey, have invented certain new and useful Improvements in Adjustable Clamps; and we do hereby declare the following to be a full, clear, and exact description of the invention, 10 such as will enable others skilled in the art to which it appertains to make and use the same, reference being had to the accompanying drawings, and to characters of reference marked thereon, which form a part of this 15 specification.

This invention relates, generally, to improvements in clamping devices for various purposes; and, the said invention has reference, more particularly, to a novel construction 20 of adjustable clamp, adapted to carry a head-rest, the clamp being adapted to be secured in a fixed position upon the back of a chair, but certain parts of the clamp being variously adjustable, so as to change 25 the angular position of the head-rest, according to the person seated or reclining in the chair.

The present invention has for its principal object to provide a novel and simply 30 constructed clamp comprising a main clamping means for securing the device in a fixed position upon the back of a chair, said clamping means carrying an element adapted to receive the stem of a head-rest, said 35 element being pivotally and adjustably mounted with relation to the clamping means, for variously adjusting the head-rest and to readily change the angular position of the latter, according to the person seated 40 or reclining in the chair, and without changing the fixed and clamped position of the main clamping means of the device.

Other objects of the present invention not at this time more particularly enumerated 45 will be clearly understood from the following detailed description of the present invention.

With the various objects of the present invention in view, the said invention consists, primarily, in the novel adjustable clamping device hereinafter set forth; and, the said invention consists, furthermore, in the novel arrangements and combinations 50 of the various devices and parts, as well as 55 in the details of the construction of the said

parts, all of which will be more fully described in the following specification, and then finally embodied in the clauses of the claims which are appended to and which form an essential part of the said specification. 60

The invention is clearly illustrated in the accompanying drawings, in which:—

Figures 1 and 2 are two side elevations of 65 an adjustable clamp, showing one embodiment of the principles of the present invention, the clamping means of the device being represented in its fixed clamping relation with the head-board of a chair or other support, and the pivoted head-rest carrier being 70 represented in two of its adjusted positions.

Fig. 3 is a face view of the clamp, looking 75 in the direction of the arrow *x* in said Fig. 1; and Fig. 4 is a similar view of the clamp, looking in the direction of the arrow *y* in said Fig. 1.

Fig. 5 is a top or plan view of the device, with the parts as shown in said Fig. 1; Fig. 6 is a horizontal representation of the device, said section being taken on line 6—6 80 in said Fig. 1; and Fig. 7 is a similar sectional representation, taken on line 7—7 in said Fig. 1.

Similar characters of reference are employed in all the said above described views, 85 to indicate corresponding parts.

Referring now to the several figures of the drawings, the reference-character 1 indicates a fragmentary portion of the top or head-board of a chair, which may be of 90 any suitable construction and shape, and with which the clamping means of the device is adapted to be brought into a fixed clamped relation, in the manner to be presently more fully described, and substantially 95 as shown in Figs. 1 and 2 of the drawings.

The adjustable clamp is generally indicated by the reference-character 2, and the same comprises a main clamping element 100 consisting, essentially, of a curved member 3 provided at its respective end-portions 4 and 5 with a pair of downwardly extending clamping legs or fingers 6 and 7. Upon its convexly formed surface 8, the said curved member 3 has a rearwardly projecting ear 105 or lug 9, which is provided with a laterally extending hole or perforation 10 for the reception of a pivot-pin or pintle 11. Extending in an upward direction from said ear or lug 9, and preferably located to one side of 110

the ear or lug, is a projection, as 12, forming a stop-post for the purposes to be presently more fully described.

Pivottally connected with the said rearwardly projecting lug or ear 9, by means of the projecting end-portions of the pivot-pin or pintle 11, are correspondingly located and perforated ears or lugs 14 of a plate or member 13, said plate or member being formed with a marginal and tubular stem or shank-receiving socket, as 15, which is slotted or has a saw-cut, as at 16, and is provided with a pair of screw-threaded tightening lugs or ears 17 and 18, and a tightening or binding screw 19, for securely clamping in a vertically adjusted position, within said tubular socket 15, the shank or stem of a suitable head-rest, or other suitable element, as will be clearly understood from an inspection of the several figures of the drawings. In the upper portion of said plate or member 13 is a screw-threaded hole 20, indicated in dotted outline in Fig. 5 of the drawings, and movably disposed in said hole 20 is a screw-threaded shank or bolt 21, provided at one end with means 22, such as a hand-wheel, or other suitable means of rotating said shank or bolt, for bringing the other end 23 of said shank or bolt into active contact with the flat face 24 of the previously mentioned projection or stop-post 12, and to thereby move the said plate or member 13 and its receiving socket 15 into different angular relations to the member 3, as is indicated in Figs. 1 and 2 of the drawings. At its lower end, the said pivoted or hinged plate or member 13 is provided with another screw-threaded hole, as 25, in which is rotatably mounted a screw-threaded shank or bolt 26, provided at its outer end with an operating means 27, such as a hand-wheel or other suitable means for rotating said shank or bolt.

The reference-character 28 indicates a suitably formed clamping plate, preferably provided in its chair-engaging surface with longitudinally extending channels or grooves, as 29, said plate being also formed with a socket or depression, as 30. Upon its surface, the said plate 28 is formed with a concaved or dished-out depression, as 31, which is connected with the socket or depression 30 by a hole or tubular portion 32. Suitably and loosely disposed in said hole or tubular portion 32 is the shank of a screw 33, said screw having its head 34 disposed in said socket or depression 30, and the other end of said screw 33 being suitably screwed into the end of the previously mentioned screw-threaded shank or hole 25, as shown in Fig. 7 of the drawings, and whereby the said clamping plate 28 is connected with said shank or bolt 26, so as to have a freely oscillating relation with reference to the end of said shank or bolt, and with reference to the

plate or member 13, to enable the said shank or bolt 26 and the plate or member 13 to assume different angular relations to the face of the said clamping 28, when in its clamped position upon the head-board of a chair, as will be clearly evident from an inspection of Figs. 1 and 2 of the drawings. If desired, the said clamping plate 28 may be formed along one of its edges with a flange, as 35, which extends along the corresponding side-edge of the plate or member 13, thus preventing excessive lateral movement of the said clamping plate 28, as will be clearly evident.

Having in the foregoing description set forth the general construction of an adjustable clamp, showing one embodiment of the principles of the present invention, we will now briefly set forth the manner of its attachment to the head-board of a chair, or other object, and the manner of producing the various adjustments of the plate or member 13.

The various members or elements 6 and 7 and 28 are first placed upon or against the opposite faces of the member 1, with the member 3 placed above the member 1, the clamping 28, by means of turning the shank or bolt 26, so that it will move in the direction of the arrow α , see Fig. 7, clamping the device in its securely fixed position upon said element or member 1. The shank or bolt 21 is now turned so as to move in the same direction, until its free end-portion 23 is in firm biting engagement with the surface 24 of the stop-post 12, all of the various members of the device thereby being secured in immovable relation to each other. The stem of a head-rest, or other shank when now inserted in the socket-member 15 may be raised or lowered, and secured in the desired position, against movement, by the clamping ears or lugs 17 and 18 and the tightening screw 19, as will be clearly evident.

One of these positions is indicated in Fig. 1 of the drawings. Now, suppose it is desired to change the relative positions of the various elements from these represented in said Fig. 1 to the positions shown in Fig. 2 of the drawings. The shank or bolt 21 is now unscrewed, so as to move in a direction opposite to that indicated by the arrow α . The shank or bolt 26 is thereupon also turned, so as to move in a direction opposite from that indicated by the arrow α , the result being that the lower portion of the plate or member 13 will move forward upon the shank or bolt 26, in a direction toward the clamping plate 28, the said plate or member swinging upon an arc having its center in the central axis of the pintle 11, as will be evident, thereby bringing the said shank or bolt 26, the said plate 13, and the receiving socket 15 into another angular re-

lation, such as is indicated in said Fig. 2. To permanently secure the several elements, thus adjusted, in their clamped position upon the member 1, the shank or bolt 21 is again turned, so as to move in the direction of the arrow α , until the end 23 of said shank or bolt 21 is again brought into biting engagement with the flat face 24 of the stop-post 12, whereby all the members of the 10 vice are again secured in immovable relation to each other.

Of course it will be understood, that by the proper manipulations of the screw-shanks or bolts 21 and 26, in the manner herein-above described any other desirable 15 adjustments may be made.

We are fully aware that changes may be made in the various arrangements and combinations of the several devices and parts, 20 as well as in the details of the construction of the said parts, without departing from the scope of the present invention as set forth in the foregoing specification, and as defined in the clauses of the claims which 25 are appended thereto. Hence, we do not limit our present invention to the exact arrangements and combinations of the several devices and parts as described in the said specification, nor do we confine ourselves 30 to the exact details of the construction of the said parts, as illustrated in the accompanying drawings.

We claim:

1. An adjustable clamp comprising a pair 35 of clamping members, a carrier-means pivotally connected with one of said clamping members, and mechanism carried by and co-operating with said carrier-means for moving said carrier-means with relation to said 40 clamping members, said means also co-operating with said clamping members for bringing them into a fixed clamping relation with an object.

2. An adjustable clamp comprising a pair 45 of clamping members, a carrier-means pivotally connected with one of said clamping members, and mechanism carried by and co-operating with said carrier-means for moving said carrier-means with relation to said 50 clamping members, said means also co-operating with said clamping members for bringing them into a fixed clamping relation with an object, and mechanism also carried by said carrier-means and co-operating therewith for securing said clamping 55 means and said carrier-means immovably with relation to each other.

3. An adjustable clamp comprising a pair 60 of clamping members, a carrier-plate pivotally connected with one of said clamping members, said carrier-plate having a screw-threaded hole, and a screw-threaded shank rotatably mounted in said screw-threaded hole, for moving said carrier-plate with relation to said clamping member, and said

screw-threaded shank being adapted to bear against the other clamping member for bringing them into a fixed clamping relation with an object.

4. An adjustable clamp comprising a pair 70 of clamping members, a carrier-plate pivotally connected with one of said clamping members, said carrier-plate having a screw-threaded hole, and a screw-threaded shank rotatably mounted in said screw-threaded 75 hole, for moving said carrier-plate with relation to said clamping member, and said screw-threaded shank being adapted to bear against the other clamping member for bringing them into a fixed clamping relation with 80 an object, said carrier-plate being provided with a second screw-threaded hole, and a screw-threaded shank rotatably mounted in said last-mentioned hole, said last-mentioned shank co-operating with said first-mentioned 85 clamping member and said carrier-plate for securing said clamping members and said carrier-plate immovably with relation to each other.

5. An adjustable clamp comprising a main 90 clamping member, a stop-post extending from said clamping member, a carrier-plate pivotally connected with said clamping member, said carrier-plate being provided with a screw-threaded hole, and a screw-threaded 95 shank rotatably mounted in said hole, and adapted to be brought into biting retaining engagement with said stop-post.

6. An adjustable clamp comprising a main 100 clamping member, a stop-post extending from said clamping member, a carrier-plate pivotally connected with said clamping member, said carrier-plate being provided with a screw-threaded hole, and a screw-threaded 105 shank rotatably mounted in said hole, and adapted to be brought into biting retaining engagement with said stop-post, and a second clamping member carried by said carrier-plate.

7. An adjustable clamp comprising a main 110 clamping member, a stop-post extending from said clamping member, a carrier-plate pivotally connected with said clamping member, said carrier-plate being provided with a screw-threaded hole, and a screw-threaded 115 shank rotatably mounted in said hole, and adapted to be brought into biting retaining engagement with said stop-post, a second clamping member, and means for oscillatorily connecting said second clamping member 120 with said carrier-plate.

8. An adjustable clamp comprising a main 125 clamping member, a pivot-lug extending rearwardly from said member, and a stop-post extending in an upward direction from said member, a carrier-plate provided with perforated ears, a pintle mounted in said ears and in the pivot-lug of said clamping member, a stem-receiving socket-member connected with said carrier-plate, said socket-mem- 130

ber having a slotted portion, clamping-lugs extending from said slotted portion, said carrier-plate being provided with a screw-threaded hole, and a screw-threaded shank 5 rotatably mounted in said hole, and adapted to be brought into biting retaining engagement with said stop-post.

9. An adjustable clamp comprising a main clamping member, a pivot-lug extending 10 rearwardly from said member, and a stop-post extending in an upward direction from said member, a carrier-plate provided with 15 perforated ears, a pintle mounted in said ears and in the pivot-lug of said clamping member, a stem-receiving socket-member connected with said carrier-plate, said socket-member having a slotted portion, clamping-lugs extending from said slotted portion, said carrier-plate being provided 20 with a screw-threaded hole, a screw-threaded shank rotatably mounted in said hole, and adapted to be brought into biting retaining 25 engagement with said stop-post, and a second clamping member carried by said carrier-plate.

10. An adjustable clamp comprising a main clamping member, a pivot-lug extending 30 rearwardly from said member, and a stop-post extending in an upward direction from said member, a carrier-plate provided 35 with perforated ears, a pintle mounted in said ears and in the pivot-lug of said clamping member, a stem-receiving socket-member connected with said carrier-plate, said 40 socket-member having a slotted portion, clamping-lugs extending from said slotted portion, said carrier-plate being provided with a screw-threaded hole, a screw-threaded shank rotatably mounted in said hole, and 45 adapted to be brought into biting retaining engagement with said stop-post, a second clamping member, and means for oscillatorily connecting said second clamping member with said carrier-plate.

11. An adjustable clamp comprising a main clamping member, a stop-post extending 50 from said clamping member, a carrier-plate pivotally connected with said clamping member, said carrier-plate being provided 55 with a screw-threaded hole, a screw-threaded shank rotatably mounted in said hole, and adapted to be brought into biting retaining engagement with said stop-post, said carrier-plate being provided with another screw-threaded hole, a second screw-threaded shank

rotatably mounted in said last-mentioned hole, and a second clamping member attached to the end-portion of said last-mentioned screw-threaded shank.

12. An adjustable clamp comprising a main clamping member, a stop-post extending 60 from said clamping member, a carrier-plate pivotally connected with said clamping member, said carrier-plate being provided with a screw-threaded hole, a screw-threaded shank rotatably mounted in said 65 hole, and adapted to be brought into biting retaining engagement with said stop-post, said carrier-plate being provided with another screw-threaded hole, a second screw-threaded shank rotatably mounted in said 70 last-mentioned hole, a second clamping member attached to the end-portion of said last-mentioned screw-threaded shank, and a means of oscillatory connection between said 75 second clamping member and said last-mentioned screw-threaded shank.

13. An adjustable clamp comprising a main clamping member, a stop-post extending 80 from said clamping member, a carrier-plate pivotally connected with said clamping member, said carrier-plate being provided with a screw-threaded hole, a screw-threaded shank rotatably mounted in said 85 hole, and adapted to be brought into biting retaining engagement with said stop-post, said carrier-plate being provided with another screw-threaded hole, a second screw-threaded shank rotatably mounted in said 90 last-mentioned hole, a second clamping member, said second clamping member being provided in its opposite faces with receiving 95 depressions and a tubular connection between said depressions, and a screw having a head located in one of said depressions, said screw being loosely mounted in said tubular connection and having its opposite end screwed into the end-portion of said last-mentioned screw-threaded shank for oscillatorily connecting said last-mentioned 100 clamping plate to the end of said last-mentioned screw-threaded shank.

In testimony, that we claim the invention set forth above we have hereunto set our hand this 15th day of April, 1921.
